INVENTOR

P. P. Brown,

BY *Lawrence D. M. Brown*

ATTORNEYS

UNITED STATES PATENT OFFICE.

PETER P. BROWN, OF LUSK, WYOMING.

WINDOW PROTECTOR.

Application filed May 23, 1924. Serial No. 715,384.

To all whom it may concern:

Be it known that I, PETER P. BROWN, a citizen of the United States, and resident of Lusk, in the county of Niobrara and State of Wyoming, have invented certain new and useful Improvements in Window Protectors, of which the following is a specification.

This invention relates to improvements in protectors for windows, and it consists in 10 the combinations, constructions and arrangements herein described and claimed.

An object of the invention is to provide a simple and reliable device adapted to be attached to the frame or sash of a window 15 and to then afford facilities for bracing the window panel or pane so that the pane is not likely to be broken because of wind pressure thereagainst or like stresses.

A further object of the invention is to provide in a device of the character described 20 an extremely strong and durable member for supporting on a window frame or sash means engageable with the window pane to brace the latter.

A still further object of the invention is 25 to provide a device of the character described which is adapted to be secured in any one of a plurality of suitable positions on a window frame without the use of any 30 special tools and without requiring the exercise of any unusual skill.

A still further object of the invention is 35 to provide a device of the character described which will not in any way interfere with the manipulation or adjustment of the relatively movable parts of a window to which the device has been applied.

Other objects and advantages will be apparent from the following description, considered in conjunction with the accompanying drawing, in which

Figure 1 is a fragmentary perspective view showing a window equipped with a device embodying the invention,

Figure 2 is a plan view of the device,

Figure 3 is an edge view of the device,

Figure 4 is an enlarged fragmentary sectional view of a presser head which is comprised in the device.

50 In Figure 1, the numeral 1 designates a

window frame of ordinary construction and 2 denotes a window sash that is mounted in the frame and may be slidable vertically therein in the usual manner. The window sash carries one or more panes of glass, as 55 at 3 and as is usual in ordinary window constructions.

The pane 3 is relatively frangible and is likely to be broken by any stress or pressure against a face thereof, as for instance as a 60 result of wind pressure against the outer face thereof.

My invention contemplates the provision of means for protecting the window pane against breakage which might otherwise result because of the application of wind pressure or like stresses against the window pane. Use of the device also tends to prevent movement of the window pane and sash as a unit relatively to the frame and 70 thus further lessens the possibility of accidental breaking of the window pane.

In carrying out the invention, I provide an arm indicated generally at 4 which preferably is of trussed construction and comprises a frame having a pair of side bars 5 converging together at one end, as at 6, the side members 5 being connected at their other ends by cross bar 6 and being stayed to each other by pairs of crossed diagonally 80 extending stay members 7. The frame of the member 4 thus has substantially the form of an elongated triangle and the member 4 also may be referred to as tapering in width from one of its ends to the opposite 85 end thereof.

The member 4 is enlarged at the juncture of the first named ends of the side bars 5 and the enlarged portion is bored to provide a sleeve or eye member 8, the axis of 90 which extends substantially at right angles to the direction of length of the member 4.

The arms 5 are extended at their second named ends beyond their points of juncture with the cross bar 6 to provide a pair of 95 parallel spaced apart ears 9. The respective ears 9 are provided with aligned openings for the reception of a pintle 10 which also extends through aligned openings in spaced apart parallel lugs or ears 11 which 100

are carried by an attaching plate 12, whereby the member 4 will be supported on the attaching plate 12 to swing about the axis of the pintle 10. The lugs 11 preferably are spaced apart a distance slightly greater than the distance between the remote faces of the ears 9 so that the member 4 will be supported with one of the ears 9 against the inner face of one of the lugs 11 and the other ear 9 against the inner face of the other lug 11 when the member 4 is swingingly supported upon the plate 12 in the manner just described, whereby the member 4 and the plate 12 will reinforce each other to a certain extent while not precluding swinging movement of the member 4 in respect to the plate 12. A line extending through the centers of the openings in the ears 9 is substantially parallel to the axis 20 of the sleeve or eye member 8.

The plate 12 preferably is substantially T-shaped and is provided with openings 13 for the reception of screws or like fastening devices 14, whereby the attaching plate 25 12 may be secured to the jamb or other portion of the window frame 1 so that the axes of the sleeve or eye member 8 and of the pintle 10 will be horizontal. When the attaching plate 12 is secured to a jamb of the 30 window frame as illustrated in Figure 1, the member 4 will be swingable vertically in parallel adjacent relation to one of the window panes 3. An adjusting screw 15 which threadedly engages the wall of the 35 opening of the sleeve or eye member 28 is connected at its end proximate to the window pane by a ball and socket joint indicated at 16 to a cap or holder 17 for a presser head 18. The latter is formed of a compressible 40 resilient material, such as rubber. A lock nut 19 adjustably engages the screw 15 and may be moved against the outer end of the sleeve or eye member 8 to lock the adjusting screw to the sleeve or eye member. A wing 45 nut 20 threadedly engages the outer end portion of the adjusting screw and may serve as a handle for manipulating the screw when the lock nut 19 has been moved out of engagement with the sleeve or eye member 8.

From the foregoing description of the various parts of the device, the operation thereof may be readily understood. The adjusting screw 15 may be manipulated to cause 55 the presser head 18 to press firmly against the pane 3 and thus to brace the pane against pressure or stresses applied against the side or face thereof opposite the presser head 18. Moreover, the engagement of the presser head 18 with the pane will tend to hold the latter and the sash therefor against movement relatively to the window frame although it will be apparent that the adjusting screw may be manipulated to re-

lease the pane from the presser head so that 65 the sash may be slid vertically or otherwise adjusted in an ordinary manner. The provision of the ball and socket joint at 16 insures that the presser head 18 will press firmly against the pane 3 when the adjusting screw has been tightened even though the pane 3 may extend in a plane not exactly at right angles to the axis of the adjusting screw 15. A brace 21 is pivotally attached at one end to the arm 4, as at 22, 70 and is engageable at its other end with any one of a vertical series of indentations 23 in the plate 12 for the purpose of supporting the arm 4 in raised position and at any one of a plurality of angular relations 75 to the perpendicular.

Obviously, my invention is susceptible of embodiment in forms other than that illustrated in the accompanying drawings and I therefore consider as my own all such modifications and adaptations of the form of the device herein described and claimed as fairly 80 fall within the scope of the appended claims.

I claim:—

1. A device of the character described comprising an arm, means whereby said arm may be swingingly supported at one end to extend in proximity to a pane of said window, a brace pivotally attached at one end to said arm and adjustably engageable at its other end with said supporting means for holding said arm in raised position and in adjusted angular relation to the vertical, a presser head adapted to engage with said window pane, an adjusting screw threadedly engaging said arm and movable axially toward and away from the plane of said window pane, and a ball and socket joint connecting the ends of said screw which is proximate to said window pane and said presser head, whereby said presser head may be moved to and from position to engage said window pane. 100

2. A device of the character described comprising an arm, means whereby said arm may be swingingly supported at one end to extend in proximity to a pane of said window, a presser head adapted to engage with said window pane, an adjusting screw 110 threadedly engaging said arm and movable axially toward and away from the plane of said window pane, and a ball and socket joint connecting the end of said screw which is proximate to said window pane and said presser head, whereby said presser head may be moved to and from position to engage said window pane, said presser head comprising a body made of a resilient compressible material. 115

3. A device of the character described comprising a supporting member of trussed elongated frame-like construction, an at-

taching plate attachable to a frame member of a window, means whereby said supporting member may be hinged to said attaching plate to swing in proximity to a pane of the window, said supporting member being formed with a sleeve at the free end thereof, the axis of said sleeve extending substantially at right angles to the plane of

said window pane, a screw threadedly engaging the inner wall of said sleeve, a 10 presser head flexibly attached to said screw at the end of the latter proximate to said window pane, and means whereby said screw may be locked to said arm in adjusted position in respect to the latter.

PETER P. BROWN.
